CLAIM

I claim the ornamental design for nurse scrub bottoms, as shown and described.

DESCRIPTION

FIG. 1 is a front view of a first embodiment of a nurse scrub bottoms;

FIG. 2 is a rear view thereof;

FIG. 3 is a right side view thereof;

FIG. 4 is a left side view thereof;

FIG. 5 is a top view thereof;

FIG. 6 is a front view thereof in combination with a scrub top;

FIG. 7 is a front view of a second embodiment of a nurse scrub bottoms;

FIG. 8 is a rear view thereof;

FIG. 9 is a right side view thereof;

FIG. 10 is a left side view thereof; and,

FIG. 11 is a top view thereof.

The broken line outline of the scrub top in FIG. 6 depicts environment associated with the claimed design, but forms no part of the claimed design. The broken lines of the nurse scrub bottoms depict portions of the article which form no part of the claimed design.
